UNITED STATES PATENT OFFICE.

FREDERICK HACHMANN, OF ST. LOUIS, MISSOURI, ASSIGNOR OF ONE-HALF TO
BERNARD G. VIETH AND ONE-FOURTH TO DAVID M. HUTCHINSON, BOTH
OF ST. LOUIS, MISSOURI.

TOY VEHICLE

1,378,023.

Specification of Letters Patent.

Patented May 17, 1921.

Application filed April 20, 1920. Serial No. 375,311.

To all whom it may concern:

Be it known that I, FREDERICK HACHMANN, a citizen of the United States, and resident of the city of St. Louis, and State 5 of Missouri, have invented certain new and useful Improvements in Toy Vehicles, of which the following is a specification containing a full, clear, and exact description, reference being had to accompanying drawings, forming a part thereof.

My invention relates to improvements in toy vehicles and has for its primary object a toy vehicle in which the front and rear wheels are adjustable, so as to raise and 15 lower the same according to the size of the child using the toy.

A further object is to construct a toy vehicle having an animal head attached to the front wheels in such a way that the 20 head and front wheels will turn simultaneously when steering the device, in which the head is so arranged and mounted that it can be constructed of a single thickness of material.

25 In the drawings,

Figure 1 is a side elevation of my device with a portion broken away and in section.

Fig. 2 is a cross sectional view of the 30 rear wheels support taken on the line 2—2 of Fig. 1, the same being drawn to an enlarged scale.

Fig. 3 is a perspective view of the rear axle support.

Fig. 4 is a vertical fragmental section of 35 the front wheels support showing the adjusting means.

Fig. 5 is an enlarged fragmental view of 40 the front portion of the vehicle showing the method of mounting the head and steering mechanism.

Fig. 6 is a top plan view of the plate for receiving the animal head.

Fig. 7 is an enlarged view of one of the 45 bolt holes showing the socket formed for receiving the square hold of the bolt.

In the construction of my device I employ a connecting means or member 8, on which is mounted the seat 9 secured to the means 8 and below the seat member 9 is 50 the vertical standard 10, this standard being rigidly secured to the member 8 in such a manner that it will not turn or move in any direction. The standard 10 is preferably cylindrical and is provided on its 55 one end with the slot 11 and adjacent the

edges of the slot with the flattened faces 12. The standard 10 is also provided with a plurality of bores 13, these bores being at a right angle to the slot 11, and in the bores 13 are placed the sleeve 14.

60

Each of the bores 13, that is the bores on the front side of the standard 10 is provided with a recess 15 which receives the square shoulder 16 formed on a bolt 17. On the opposite end of the bolt 17 is placed the thumb 65 nut 18. Secured within the slot 11 is the rear axle support 19 which has its central portion rabbeted as at 20, this rabbet being of sufficient size to fit snugly within the slot 11. Through the axle support 19 is 70 formed an opening 21, which is provided with a sleeve 22. This opening and sleeve are so arranged as to be capable of being brought in alignment with the openings 13 and sleeve 14 formed in the standard 10. 75 Through the lower portion of the axle support 19 is passed the axle 23 to which a pair of wheels 24 are attached in any well known manner.

Near the front end of the connecting 80 means 8 is formed the bore 25 through which the pin 26 passes. This pin is provided with a projecting flange 27 which is designed to contact with the under side of

the member 8 and beneath the flange 27 is 85 a cylindrical projection 28. This cylindrical projection is provided with bores 29, in which sleeves 30 are secured. This cylindrical projection 28 is designed to fit within the bore 31 formed in the front axle sup-

port 32. Through this axle support the front axle 33 is passed and on this axle are secured a pair of wheels 34. The front 90 axle support is provided with openings 35 which are likewise provided with sleeve 36 95 and a square opening 37, this construction being identical with the construction of the standard 10.

On top of the connecting means 8 is placed a circular disk 38 which is provided 100 with a cylindrical opening 39 and a groove 40. Through the cylindrical opening 39 the pin 26 is passed and in the slot 40 is inserted the animal head 41. It is to be understood of course, that I do not desire to 105 limit myself to any particular animal head or in fact an animal head, but this part of my device can be made in any fanciful shape. The head 41 is provided with a counter-bore 42 in which the upper end 110

of the pin 26 projects. The head is then secured to the pin by means of a wood screw 43. This will bind several front parts comprising the steering mechanism 5 together. The front axle support is held in position by means of the bolt 44 and thumb nut 45, and through the head 41 is passed the handle 46, this being for the purpose of steering the vehicle as this handle projects from both sides of the head.

By my improved making of the head and front members of the vehicle, it is possible to make a stronger and cheaper construction inasmuch as the twisting strain 15 on the head is divided entirely across the face of the disk and not at the point where the pin 26 is secured. This has been found to be a great drawback in the construction of one-piece heads and has been, up to the 20 present time, eliminated partially by the use of heads formed of a number of layers of veneer, but this construction has been found expensive and not nearly as satisfactory as my construction. It is to be understood that in my device four wheels are 25 made use of, two in the rear and two in the front. These wheels may be either plain disk or provided with rubber tires, or even spoked metallic wheels may be used 30 without departing from the spirit of my invention.

The pin 26, the flange 27, the cylindrical projection 28, the disk 38, the head 41 and handle 46 form the steering gear, the pin 35 26 being so mounted through the connecting member 8 as to turn freely therein while all the other parts mentioned are so connected as to turn simultaneously.

Having fully described my invention, 40 what I claim is:

1. A toy vehicle comprising a connecting member, a seat secured to the upper side of said member, a slotted standard rigidly secured to the underside of the connecting 45 member near one of its ends, a pin projecting through said connecting member and rotatable therein near its opposite end, a flange formed integral with said pin and in contact with the underside of the connecting member, a cylindrical projection formed integral with said flange, a disk 50

provided with a groove located on the upper side of the connecting member, a steering head seated in said groove and secured to said disk, said steering head adapted to be rigidly secured to the projecting end of said pin, and axle supports adjustably secured to the standard and cylindrical projection for regulating the height of the seat. 60

2. A toy vehicle, comprising a connecting member, a seat secured to said connecting member, a slotted standard rigidly secured to the connecting member, a rear axle support adjustably secured in the slot of the 65 standard, a pin projecting through the connecting member, a flange formed integral with said pin, said flange contacting with the under side of the connecting member, a cylindrical projection formed integrally 70 with said flange, a front axle support adjustably secured to the pin beneath the flange, a steering handle secured to the pin above the connecting member, and means for holding the axle supports in adjusted 75 position.

3. A toy vehicle, comprising a connecting member, a seat secured to the upper side of said member, a cylindrical slotted standard rigidly secured to the under side 80 of said connecting member near one of its ends, a pin projecting through said connecting member and rotatable therein near its opposite end, a flange formed integral with said pin and in contact with the under side of the connecting member, a cylindrical projection formed integral with said flange, a disk located on the upper side of the connecting member, a steering 85 head secured to said disk, said steering head adapted to be rigidly secured to the projecting end of said pin, and axle supports adjustably secured to the standard and cylindrical projection for regulating 90 the height of the seat. 95

In testimony whereof, I have signed my name to this specification, in presence of two subscribing witnesses.

FREDERICK HACHMANN.
